UNITED STATES PATENT OFFICE.

ARMIN ELMENDORF, OF CHICAGO, ILLINOIS, ASSIGNOR TO HASKELITE MANUFACTURING CORPORATION, A CORPORATION OF NEW YORK.

REFRIGERATOR CONSTRUCTION.

Application filed February 28, 1921. Serial No. 448,427.

To all whom it may concern:

Be it known that I, ARMIN ELMENDORF, a citizen of the United States, residing at Chicago, county of Cook, State of Illinois, 5 have invented a certain new and useful Improvement in Refrigerator Construction, and declare the following to be a full, clear, and exact description of the same, such as will enable others skilled in the art to which 10 it pertains to make and use the same, reference being had to the accompanying drawings, which form a part of this specification.

In my prior application Serial No. 442-15 406 filed February 4, 1921, I have disclosed a novel form of heat insulating material a single sheet of which may be employed to form a wall of the kind that has heretofore been made up of a plurality of sheets or 20 layers.

The present invention has for its object to produce a simple and novel design of a refrigerator or the like which will permit the aforesaid heat insulating material or a 25 similar material to be employed most advantageously.

The various features of novelty whereby my invention is characterized will herein-after be pointed out with particularity in 30 the claims; but, for a full understanding of my invention and of its object and advantages, reference may be had to the following detailed description taken in connection with the accompanying drawings, wherein:

35 Figure 1 is a top plan view of a refrigerator constructed in accordance with my invention, a portion being shown in section;

Fig. 2 is a front view of the refrigerator, a portion of the top and of one of the side 40 walls being shown in section;

Fig. 3 is a section, either horizontal or vertical, on an enlarged scale through a corner of the refrigerator shown in Figs. 1 and 2;

45 Fig. 4 is a view similar to Fig. 3, illustrating a construction adapted to be employed where rounded corners are desired;

Fig. 5 is a vertical section through the top and back wall of a modified form of 50 refrigerator;

Fig. 6 is a view similar to Fig. 5, showing only a fragment of the metal lining; and

55 Fig. 7 is a view similar to Fig. 5, showing a slightly different arrangement.

In accordance with my invention the walls of the refrigerator are made of single sheets or slabs of my improved construction material, these sheets or slabs being preferably shaped and finished in the process of manufacturing them, so that they need only be assembled by the refrigerator manufacturer. 60

In all the forms of my invention, the individual slabs are made of a thick core sheet of heat insulating material, and comparatively thin sheathing layers glued to the broad faces thereof; the construction being preferably that disclosed in my aforesaid application. Thus, in the arrangement 65

shown in Figs. 1, 2 and 3, each wall is made 70 of a thick core member, *a*, of heat insulating material, preferably cork board, an outer sheathing, *b*, and an inner sheathing, *c*. Each wall is in the form of a single panel, cut so as to make with the remaining walls 75

any desired kind of joints. In the arrangement shown, the top wall, 1, extends across the tops of the several side walls, three of which are indicated at 2, 3 and 4, while two of the side walls of which the side wall 3 is 80 one, lie between the two other side walls. The walls whose edges engage with the inner faces of the adjacent walls have their sheathing layers extended so as to cover the ends 85

or edges of the latter walls. Thus the side wall 3 has its outer sheathing, *b*, extended across the ends of the walls 2 and 4 while all of the side walls have their outer sheathing extended upwardly across the ends of the top wall 1. 90

The cork board is not a suitable material for receiving screws, nails or similar fastening means, nor is it a suitable material to insure a perfect glued joint when the slabs are assembled to form a walled structure. I 95 therefore place along the edges of the cork board core, between the sheathing layers, and forming an enclosing frame for the core, wooden cleats, *d*, which are glued in place.

The several slabs of which a refrigerator 100 is to be made having been manufactured in completed form, they need only be assembled in the proper way to produce the shell of a refrigerator; being glued together or being held together by means of screws or the like, 105 or by means of glue and screws both; the solder being placed along the lines of contact between the metal linings if the inner surfaces of the walls or slabs be of metal.

The detail of the walls and the joints is 110

shown in Fig. 3. It will be seen that the exterior sheathing is made of a comparatively thick core member, 5, of wood and facing layers, 6 and 7, of wood veneer; 5 while the inner sheathing is made up of a comparatively thick wooden core, 8, and facing layers, 9 and 10, of wood veneer, there being a layer of sheet metal, 11, overlying the veneer 10. Those of the walls which 10 have the exterior sheathing extended beyond the body portions thereof also preferably have the innermost metal layer extended and folded back over the cleats *d* as indicated at 12. The member 12 lies flat against the 15 metal sheet forming the inner surface of the adjacent wall and produces a water-tight joint. Insurance against leakage may be had by placing small fillets, 13, of solder in the corners on the inside of the refrigerator. The outer corners may be protected, 20 if desired, by means of metal corner pieces, 14. As heretofore explained, the slabs forming the two walls may be fastened and held together in any one of a plurality of ways. 25 In Fig. 4 I have illustrated an arrangement similar to that in Fig. 3, except that the upper wall or slab does not extend entirely across the upper edge of the side or back slab, leaving room for a finishing 30 piece, 15, resting against the end of the top slab and upon that portion of the side or back slab which is left uncovered by the top slab. In this arrangement the outer sheathing, *b*, of the upright slab does not project beyond the cleat, *d*. In this arrangement, also, I have illustrated how the several 35 slabs may be held together by means of screws, a long screw, 16, extending entirely through that portion of the top slab in 40 which the cleat lies, down into the cleat forming the upper edge of the underlying slab.

In Fig. 5 I have illustrated an arrangement in which the sheathing on the inner 45 side of the walls consists simply of metal, each slab having a sheet of metal, 17, between which and the core there may be interposed a layer of canton flannel or other fabric, 18, which is impregnated with blood 50 glue and insures a good joint between the metal and the cork board as explained in my prior application. The upright slab is made the full height of the structure and the horizontal slab abuts against the same, 55 the outer sheathing layer of the horizontal wall extending across the top edge of the upright wall. In this arrangement, the metal lining of the horizontal slab is continued beyond the cleat and is folded back over the 60 cleat as indicated at 19 in Figs. 5 and 6; thus giving a large area of contact between the two metal linings at each corner.

In Fig. 7 I have illustrated an arrangement similar to Fig. 3 except that the 65 wooden sheathing is omitted on that side

of the slab which in to form the inner face of the wall in each instance. In this arrangement the horizontal slab rests upon the upper edge of the upright slab; the exterior sheathing of the upright slab being continued upwardly across the end of the horizontal slab; and the marginal portions, 20, of the metal lining of the upright slab being extended and bent back over the cleats. Viewed in another aspect, 70 the construction of Fig. 7 is simply a reversal of the construction shown in Fig. 5.

If desired a metal lining, in addition to the metal lining heretofore described, or constituting the only metal lining for the refrigerator, may be formed as an independent unit and set into the refrigerator shell. 80

It will be seen that my invention makes it possible to construct efficient refrigerators very cheaply and, by reason of the use of ply-wood for stiffening purposes and cork board for insulation, refrigerators built in accordance with my invention will be much lighter than ordinary refrigerators and at 85 the same time be strong and durable. 90

While I have illustrated and described only a single form of my invention with a few slight modifications, I do not desire to be limited to the exact structural details thus illustrated and described; but intend to cover all forms and arrangements which come within the terms employed in the definitions of my invention constituting the appended claims. 95

I claim:

1. A walled structure made up of pre-formed slabs each comprising a core member of heat insulating material lying between and permanently secured to an outer sheathing and an inner metal lining, one of the walls lying against an edge of another wall, and the sheathing of the latter wall being extended across and engaging with the adjacent edge of the other wall. 100

2. A preformed wall comprising a self-supporting slab of heat insulating material, a frame of wood surrounding said slab, and a sheathing of ply-wood extending across one of the faces of said slab and engaging with and secured to said frame. 105

3. A preformed wall comprising a self-supporting slab of heat insulating material, a frame of wood surrounding said slab, and a sheathing of ply-wood extending across one of the faces of said slab and engaging with and secured to said frame, the whole being glued together. 110

4. A preformed wall comprising a self-supporting slab of heat insulating material, a frame of wood surrounding said slab and having approximately the same thickness as said slab, and sheathing members lying on opposite sides of said slab and said frame and firmly united thereto. 115

5. A preformed wall comprising a self- 120

supporting slab of heat insulating material a wooden frame surrounding said slab and having approximately the same thickness as the slab, and a sheet of ply-wood glued 5 to one face of said slab and frame and projecting beyond the frame at certain of its margins.

6. A preformed wall comprising a slab of heat insulating material, a frame of wood 10 of approximately the same thickness as the slab surrounding the latter, a sheet of ply-wood glued upon one face of the slab and frame, and a sheet of metal glued upon the opposite face of said slab and frame.

7. A preformed wall comprising a slab of heat insulating material, a frame of wood 15 of approximately the same thickness as the slab surrounding the latter, a sheet of ply-wood glued upon one face of the slab and frame, and a sheet of metal glued upon the 20

opposite face of said slab and frame, said sheet of metal being extended beyond said frame at certain of its margins and being folded back across the frame.

8. A walled structure made up of slabs 25 each formed of a core of heat insulating material having along an edge a wooden cleat of approximately the same thickness as the core, and a sheathing layer extending across one face of the core and the corresponding face of said cleat; the cleated end of one of said slabs lying against the side of a second slab and engaging with the cleat thereon; and an outer sheathing on the first 30 of said slabs extending beyond the cleat and overlying the cleat on said second slab.

In testimony whereof, I sign this specification.

ARMIN ELMENDORF.
